UNITED STATES PATENT OFFICE.

CLARK T. ANDERSON, OF MANSFIELD, OHIO, ASSIGNOR TO THE HARTMAN ELECTRICAL MANUFACTURING COMPANY, OF MANSFIELD, OHIO, A CORPORATION OF OHIO.

DESIGN FOR A RADIOCABINET.

Application filed May 6, 1925. Serial No. 13,338. Term of patent 14 years.

To all whom it may concern:

Be it known that I, CLARK T. ANDERSON, a citizen of the United States of America, residing in the city of Mansfield, county of Richland, and State of Ohio, have invented a new, original, and ornamental Design for Radiocabinets, of which the following is a specification, reference being had to the accompanying drawing, forming part thereof.

The figure is a perspective view of the radiocabinet showing my new design.

I claim:

The ornamental design for a radiocabinet as shown.

CLARK T. ANDERSON.
